(57) **CLAIM**

The ornamental design for a folding table, as shown and described.

DESCRIPTION

FIG. 1 is a front perspective view of a folding table, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, shown in a closed configuration;

FIG. 10 is a rear perspective view thereof; and,

FIG. 11 is a rear perspective view thereof, shown with the legs folded to the underframe.

The broken lines in the drawings illustrate the portions of the folding table, which form no part of the claimed design.
